UNITED STATES PATENT OFFICE.

DANIEL R. BRADLEY, OF NEW YORK, N. Y.

DESIGN FOR A PERFUMERY-BOTTLE.

SPECIFICATION forming part of Design No. 16,512, dated February 9, 1866.

Application filed January 4, 1866. Serial No. 187,694. Term of patent 3½ years.

To all whom it may concern:

Be it known that I, DANIEL R. BRADLEY, a citizen of the United States, residing at New York, in the county and State of New York, 5 have invented and produced a new and original Design for Perfumery-Bottles, of which the following is a full, clear, and exact description, reference being had to the accompanying drawing, forming part thereof.

10 The purpose of my invention is to provide a novel design for perfumery-bottles; and the leading feature of the design consists of the representation of a candle and candlestick in connection therewith.

15 In the accompanying drawing, which is a side view of my new design, the base *a*, on which the bottle rests, represents a candlestick. The bottle *B* is of a long cylindrical

shape, tapered at the upper end, *b'*. *c* is the stopper, having a tapering head, *c'*. On the 20 apex of the stopper-head is a tuft, *d*, representing the wick of the candle.

f is an upright bar extending from the candlestick-base, and *e* a band that encircles the body of the bottle *B*. 25

I claim—

A design for a perfumery-bottle, consisting of the conventionalized figure of a candle having a bar, *f*, and band *e*, and mounted on a base of the figure of a candlestick, the whole 30 having the configuration of a candle and candlestick, as shown and described.

DANIEL R. BRADLEY.
